UNITED STATES PATENT OFFICE.

ARTHUR M. BARRETT, OF WINNETKA, ILLINOIS.

TRUCK.

1,308,750.

Specification of Letters Patent.

Patented July 8, 1919.

Application filed January 21, 1916. Serial No. 73,339.

To all whom it may concern:

Be it known that I, ARTHUR M. BARRETT, a citizen of the United States, and a resident of Winnetka, in the county of Cook, State of Illinois, have invented certain new and useful Improvements in Trucks, of which the following is a specification, reference being had to the accompanying drawings.

My invention relates to trucks and particularly to that class of elevating truck adapted to be used with a plurality of platforms under any one of which the truck is adapted to be run for lifting the platform and carrying it to the desired point. It is the principal object of my invention to provide in a truck of this type a simplified construction and arrangement which can be produced cheaply and which shall be as adaptable as it can be made to effective use in close quarters. It is another object of my invention to improve trucks of this type in sundry details hereinafter pointed out. The preferred means by which I have accomplished my objects are illustrated in the accompanying drawings and are hereinafter specifically described. That which I believe to be new and desire to cover by this application is set forth in the claims.

In the drawings:

Figure 1 is a side view of my improved truck with the elevating frame in lowered position;

Fig. 2 is a top view of the truck shown in Fig. 1, but with the handle shown in section;

Fig. 3 is a longitudinal section through my truck showing the elevating frame in raised position;

Fig. 4 is a front view of my truck with the elevating frame in lowered position;

Fig. 5 is a side view of the front end of the truck with the elevating frame in raised position, showing a changed position of the handle;

Fig. 6 is a vertical cross-section on line 6—6 of Fig. 5;

Fig. 7 is a vertical cross-section taken on line 7—7 of Fig. 5;

Fig. 8 is a detail view of the front axle member;

Fig. 9 is a longitudinal vertical section taken substantially at the line 9—9 of Fig. 2, but with the elevating frame in raised position;

Fig. 10 is a longitudinal vertical section taken substantially at the line 10—10 of

Fig. 2, but with the elevating frame in raised position; and

Fig. 11 is a detail view, being substantially a vertical section taken on line 11—11 of Fig. 7.

Referring to the several figures of the drawings in which corresponding parts are indicated by the same reference characters,— 20 indicates a cross-head or bolster comprising the front member of the supporting frame of the truck, having secured to it side-bars 21—22 (see Figs. 4 and 7). The side-bars 21—22 are connected by a shaft 23 at their rear ends upon which are mounted 70 supporting wheels 24—25.

The cross-head 20 comprises a vertical sleeve 26, as is best shown in Fig. 7, in which is journaled the king-bolt portion 27 of the front axle member 28. Mounted in 75 the axle member 28 is a shaft or axle 29, mounted upon which are two supporting wheels 30—31. The king-bolt 27 is retained in the bearing sleeve 26 by means of a flanged plate 32 which extends down into the sleeve 26, being secured to the king bolt 27 by any suitable means, as by bolts 33 as shown in Fig. 11. In the construction shown, the king-bolt 27 is provided with notches 34 into which lugs 35 carried by 85 the plate 32 extend for strengthening the connection of the plate 32 and the king-bolt 27.

36 indicates the front cross-bar of an elevating frame which is movable up and down 90 relative to the supporting frame 22 of the truck. The elevating frame comprises side-bars 37—38 secured at their front ends to the cross-bar 36, being secured together at their rear ends by a rod 39 (see Fig. 2). 95 Links 40—41 having their lower ends mounted on the shaft 23 are mounted at their upper ends upon a cross-rod 42 mounted in the side-bars 37—38 near the rear ends of said side-bars. Additional links 43—44 connect the rod 42 with the shaft 23, serving to reinforce the links 40—41. As will be readily understood, when the elevating frame is drawn forward relative to the supporting frame, the rear ends of the side-bars 100 37—38 will be raised out of contact with the side-bars 21—22 through the action of the link connections between the supporting frame and the elevating frame.

Means is provided, as hereinafter described, for simultaneously drawing the elevating frame forward and raising its front

end. In order to provide for a proper descent of the front end of the elevating frame relative to the supporting frame independently of the raising means, I have provided 5 diagonally-disposed slide-blocks. In the construction shown (see Fig. 10), a chamfered extension 45 depending from the cross-bar 36 at each side co-operates with a chamfered rearward extension 46 carried by the 10 cross-head 20. In order to ease the descent of the elevating frame as the extension 45 slides down the extension 46, I have provided a dash-pot 47, the piston 48 of which is pivotally connected to the cross-bar 36 by 15 means of a pin 49. The dash-pot is connected at its rear end with the supporting frame by means of a rounded head 50 which bears against the transverse portion of a yoke 51 secured to the supporting frame as best 20 shown in Fig. 2, the yoke 51 being reinforced by a transverse bar 52 at one end and a transverse bar 52^a at its other end. The head 50 is movably secured to the yoke 51 and the cross-bar 52 by means of cap-screws 25 53 extending through flaring openings 54 provided in said yoke and said cross-bar.

Means is provided in connection with the diagonal slide-blocks for holding the elevating frame in its raised position comprising 30 a hook 55 secured to the cross-head 20 adapted to be automatically engaged by a foot-latch 56 which is pivotally mounted upon the cross-bar 36 in position to be readily operated by the foot of the operator for 35 releasing it from the hook 55. A spring 57 serves to hold the foot-latch 56 turned to the limit of its movement in clockwise direction in Fig. 9, as limited by suitable stops of any appropriate type.

40 By my construction I have provided for raising the front end of the elevating frame and moving it forward relative to the supporting frame by the use of the handle by which the front supporting wheels are 45 turned about the king-bolt. In the construction illustrated this is accomplished by a direct engagement of the handle with the elevating frame. In order to accomplish this result without materially lessening the 50 adaptability of the truck for use in close quarters, I have mounted the handle upon a movable fulcrum. With the pivot point of the handle in its uppermost and rearmost position, it is adapted to be used for elevating 55 purposes; when moved downward and forward the handle is adapted to clear the elevating frame so as to permit free swiveling of the front wheels upon the king-bolt.

60 The plate 32 which serves to hold the king-bolt 27 within the bearing sleeve 26 is provided with lugs 58 extending upward therefrom. Each of these lugs is provided with a diagonally-extending slot 59, the said two slots 59 serving to movably support a 65 pivot pin 60 mounted in the handle 61. The

70 handle 61 is turned at its lower end substantially at right angles to the major portion of its length, being provided with a notch 62 a short distance to one side of the pivot pin 60. With the elevating frame in its lowered position, and with the pin 60 of the handle 61 moved to its uppermost and rearmost position, the notch 60 is adapted to be brought, by a slight movement of the handle in clockwise direction in Fig. 1, into engagement with the elevating frame, a pin 63 being provided to furnish a bearing for the handle on such frame. Upon the further movement of the handle in clockwise direction in Fig. 1, the front end of the elevating 80 frame will be moved upward and forward, as shown by a comparison of Figs. 1 and 3, the rear end of the elevating frame being at the same time raised through the action of the links by which it is connected with the 85 supporting frame. In the construction shown, a bracket 64 formed integrally with the cross-bar 36 is provided for supporting the bearing pin 63 of the elevating frame, the bracket being bifurcated at its upper end 90 to provide spaced supports for said pin.

95 As is shown in Fig. 5, the turned end of the handle 61, when the pin 60 is in its lowered forward position, and with the elevating frame in its raised position, is adapted to clear the elevating frame so as to permit the handle to be turned vertically from horizontal position to vertical position, and to be turned horizontally entirely about the king-bolt except as such turning is limited 100 by the engagement of the longer arm of the handle with the elevating frame. As will be appreciated from an inspection of Fig. 1, the same freedom of movement of the handle is attained with the elevating frame in its lowered position and with the pin 60 in its lowered forward position. Thus with the elevating frame either raised or lowered the supporting wheels 30-31 are free to be turned as desired relative to the vertical 110 bearing sleeve 26 for the king-bolt 27, whereby the truck can be readily manipulated in close quarters as may be required.

115 I have found from practice that when the pin 60 is pushed to the upper ends of the slots 59 and pressure is applied to the handle to give it an operative stroke for raising the elevating frame, such an operative stroke can easily be effected without danger of the pin 60 moving downward along said 120 slots. In this operation, in the construction illustrated, the slide-block 45 is lifted out of contact with the slide-block 46, such slide-blocks being brought into effective operation only to assist the hook 55 and the latch lever 125 56 in holding the elevating frame in raised position and subsequently in the lowering of the elevating frame relative to the supporting frame.

130 By reason of the foot-latch 56 being

mounted on the elevating frame, the same action which releases the latch 56 from the hook 55 also tends to move the elevating frame downward. Moreover if it is desired, the attendant can, after releasing the foot-lever 56, without changing his position apply the required pressure for causing the downward movement of the elevating frame. This is important, inasmuch as the weight 10 of the elevating frame, as it is desirable to make it, is barely sufficient to cause such frame to descend against the resistance of the dash-pot which is ordinarily adjusted for resisting the descent of heavy loads. In 15 the construction shown, I have provided a spring 47^a for assisting in the downward movement of the elevating frame, as will be readily appreciated.

So far as I am aware, I am the first in the 20 art to provide a movable fulcrum for a truck handle by which the handle may be utilized for raising the elevating frame without materially decreasing the adaptability of the truck for its desired movements, and my claims are to be construed accordingly.

What I claim as my invention and desire to secure by Letters Patent, is—

1. In a truck, the combination of a main 30 frame, a supporting wheel journaled upon a horizontal axis and adapted to turn about a vertical axis relatively to said frame, a handle operatively connected with said supporting wheel for guiding the truck, an upwardly-movable elevating frame mounted on said main frame, and means rigidly carried by said handle and movable therewith into and out of position to directly engage said elevating frame for lifting the same.

40 2. A truck comprising a main frame, a steering wheel connected therewith, a handle connected with said steering wheel for guiding the same, said handle being pivoted to swing in a vertical plane, an elevating frame 45 mounted on said main frame and movable up and down relatively thereto, and means rigidly carried by said handle and adapted to directly engage and lift said elevating frame when said handle is swung downwardly.

50 3. In a truck, the combination of a frame, a lever operatively connected with said frame and adapted to swing relative thereto in either of two positions thereon, and an elevating frame movable relative to said first-named frame, said lever being adapted to swing in one position upon its connections independently of the elevating frame and adapted alternatively by swinging in the 60 other position upon its connections to directly engage said elevating frame for raising it relative to said first-named frame.

4. In a truck, the combination of a frame, an elevating-frame movable up and down 65 relative to said first-named frame, and a

lever connected with said first-named frame on a fulcrum which is movable relative to said first-named frame independently of any lateral swinging of the lever, said lever being adapted to be given a swinging movement about its fulcrum as an axis independently of said elevating frame when the fulcrum is in one position, and being adapted by a swinging movement about its fulcrum as an axis when the fulcrum is in another 70 position to have direct engagement underneath a portion of said elevating frame for raising said frame relative to said first-named frame.

5. In a truck, the combination of a frame, 80 an elevating-frame movable up and down relative to said first-named frame, and a lever mounted on a fulcrum movable upward and backward relative to said first-named frame, said lever being adapted to be 85 given a swinging movement without contacting with the elevating-frame when the fulcrum of the lever is in its lower forward position and being adapted by an operative stroke with the fulcrum in its upper rear-most position to have direct engagement with said elevating-frame for moving said frame upward relative to the first-named frame.

6. In a truck, the combination of a frame, 90 a front axle-member revolvably mounted on a vertical axis upon said frame, supporting means for said front axle-member comprising a supporting wheel journaled thereon on a horizontal axis, an elevating frame 100 movable up and down relative to said first-named frame, and a handle connected with said axle-member for turning it for guiding the truck, the connections between said axle-member and said handle comprising a slot 105 in said axle-member, and a pin carried by said handle and adjustable to either of two operative positions along said slot, said handle being adapted to swing without contacting with the said first-named frame 110 when the pin is in one of its said two positions and being adapted by an operative stroke with the pin in its other operative position to directly engage said elevating-frame and to move said frame upward relative 115 to the first-named frame.

7. In a truck, the combination of a frame, a front axle-member revolvably mounted on a vertical axis upon said frame, supporting means for said front axle-member comprising a supporting wheel journaled thereon on a horizontal axis, an elevating-frame 120 movable up and down relative to said first-named frame, and a handle connected with said axle-member for turning it for guiding the truck, the connections between said axle-member and said handle comprising a slot 125 in said axle-member extending diagonally upward and backward, and a pin carried by said handle and movable along said slot, 130

- said handle being adapted to swing without contacting with the elevating-frame when the pin is in the lower forward end of said slot and being adapted by an operative 5 stroke with the pin in the upper rearward end of said slot to have direct detachable engagement with said elevating-frame for moving said frame upward relative to the first-named frame.
- 10 8. In a truck, the combination of a frame, a supporting wheel, a king-bolt connecting said supporting wheel with said frame, a handle operatively connected with said king-bolt for turning said supporting wheel about 15 the king-bolt as an axis for guiding the truck and also adapted to swing vertically, and an elevating frame movable relative to said first-named frame, the connections between said king-bolt and said handle comprising 20 a bracket carried by said king-bolt and provided with an obliquely-extending slot, and a pivot pin mounted in the handle and movable longitudinally of said slot, whereby said handle is adapted in its lowered forward position in said slot to swing independently of the elevating frame and is adapted by a stroke in its rearward uppermost position in said slot to engage said elevating frame for raising it relative to said first-named frame.
- 25 9. In a truck, the combination of a frame, a supporting wheel journaled upon a horizontal axis and adapted to turn upon a vertical axis relative to said frame, a handle operatively connected with said supporting 30 wheel for turning it about said vertical axis for guiding the truck and also adapted to swing vertically, and an elevating frame movable relative to said first-named frame, the connection between said supporting wheel and said handle being adjustable whereby the handle is adapted to be operated in either of two positions, said handle being adapted in one position to swing independently of said elevating frame and adapted by a stroke in the other position to effect a detachable engagement with a rigid portion of the elevating frame for raising said elevating frame relative to said first-named frame.
- 35 10. A truck comprising a main frame, a steering wheel connected therewith, a handle connected with said steering wheel for guiding the same, said handle being pivoted to swing in a vertical plane, an elevating frame mounted on said main frame and movable up and down relatively thereto, and means rigidly carried by said handle and adapted to directly engage and lift 40 said elevating frame when said handle is swung downwardly, said handle being movable into and out of operative relation with said elevating frame.
- 45 11. In a truck, the combination of a frame, a supporting wheel, a king-bolt connecting 50 said supporting wheel with said frame, a handle in the form of a bell crank lever pivotally mounted at its angle on a horizontal axis on said king-bolt for turning said supporting wheel about the king-bolt as an 55 axis for guiding the truck, and an elevating frame movable relative to said first-named frame, the connections between said lever and said king-bolt comprising a pivot pin and slot along which the pivot pin is movable, whereby the short arm of the lever is adapted to swing independently of the elevating frame in one position of the lever relative to the slot, and whereby said short arm of the lever is adapted by a stroke in the other position of the lever relative to the slot to detachably engage said elevating frame for raising it relative to said first-named frame.
- 60 12. In a truck, the combination of a frame, supporting wheels mounted thereon, a lever operatively connected with said frame and adapted to swing vertically relative thereto, and an elevating frame movable relative to said first-named frame, the connections between said lever and said first-named frame being movable relative to said first-named frame whereby the said lever is adapted to swing in one position independently of the elevating frame and is adapted by a stroke 65 in its other position to detachably engage said elevating frame for raising it relative to said first-named frame, such engagement of the lever with the elevating frame serving to prevent the lever from moving out of its operative elevating position.
- 65 13. In a truck, the combination of a frame, supporting wheels mounted thereon, a lever operatively connected with said frame and adapted to swing vertically relative thereto, and an elevating frame movable relative to said first-named frame, the connections between said lever and said first-named frame being movable relative to said first-named frame whereby the said lever is adapted to swing in one position independently of the elevating frame and is adapted by a stroke 70 in its other position to detachably engage said elevating frame for raising it relative to said first-named frame, said lever being provided with a suitable notch adapted to be brought into engagement with the elevating frame serving to prevent the lever from moving during the raising operation out of its effective elevating position.
- 75 14. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 80
- 85 15. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 85
- 90 16. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 90
- 95 17. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 95
- 100 18. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 100
- 105 19. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 105
- 110 20. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 110
- 115 21. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 115
- 120 22. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 120
- 125 23. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 125
- 130 24. In a truck, the combination of a frame, an elevating frame movable relative thereto, elevating links pivotally connecting the rear ends of said frames, obliquely-disposed slide-blocks mounted on said frames near their forward ends adapted to coöperate for supporting the forward end of the elevating frame during the lowering operation, and means coöperating with said links for raising said elevating frame relative to said 130

first-named frame and serving during the raising operation to move said slide-blocks out of operative engagement with each other.

15. In a truck, the combination of a frame, an elevating frame, means connecting the rear end portions of said frames adapted upon movement of one frame longitudinally relative to the other to raise or lower the rear end of said elevating frame relative to said first named frame, supporting means carried by the forward end portions of said frames respectively adapted to hold the forward end of said elevating frame in raised position when said frames are held against longitudinal movement relative to each other after a raising operation, and a lever operatively connected with one of said frames near its forward end adapted by itself by an operative stroke in engagement with the other frame to raise the forward end of the elevating frame without the aid of said supporting means and at the same time to move one of said frames longitudinally relative to the other for raising the rear end of the elevating frame relative to the other frame.

20 16. A truck comprising a main frame, a steering wheel connected therewith, an elevating frame movably mounted on said main frame, a handle connected with said steering wheel for guiding the same, and means carried by said handle and adapted to operatively engage said elevating frame to lift the same when said handle is swung in one direction, the pivot of said handle being shiftable to move said handle into and out of operative relation to said elevating frame.

25 17. A truck comprising a main frame, a

steering wheel connected therewith, an elevating frame mounted on said main frame to move forward and upward relatively thereto, a handle connected with said steering wheel for guiding the same, said handle being pivoted to swing in a vertical plane and the pivot of said handle being shiftable toward and from said elevating frame, and means rigidly carried by said handle and adapted to engage and lift said elevating frame when said handle is moved into operative relation to said elevating frame. 50

18. A truck comprising a main frame, a steering wheel connected therewith, an elevating frame mounted on said main frame to move forward and upward relatively thereto, a handle connected with said steering wheel for guiding the same, said handle being pivoted to swing in a vertical plane and the pivot of said handle being shiftable toward and from said elevating frame, and means rigidly carried by said handle and adapted to directly engage and lift said elevating frame when said handle is moved into operative relation to said elevating frame. 55

19. A truck comprising a main frame, a steering wheel connected therewith, a handle connected with said steering wheel for guiding the same, said handle being pivoted to swing in a vertical plane, an elevating frame mounted on said main frame to simultaneously move forward and upward relatively thereto, and means rigidly carried by said handle and adapted to engage and lift said elevating frame when said handle is swung downwardly. 60 70 65

ARTHUR M. BARRETT.
